(57) **CLAIM**

The ornamental design for a dental implant applied to cranial fossa and condylar plate, as shown and described.

DESCRIPTION

FIG. 1 is a perspective view of an embodiment of the present design;

FIG. 2 is a front view of the embodiment of FIG. 1 of the present design;

FIG. 3 is a rear view of the embodiment of FIG. 1 of the present design;

FIG. 4 is a right side view of the embodiment of FIG. 1 of the present design;

FIG. 5 is a left side view of the embodiment of FIG. 1 of the present design;

FIG. 6 is a top view of the embodiment of FIG. 1 of the present design;

FIG. 7 is a bottom view of the embodiment of FIG. 1 of the present design;

FIG. 8 is a perspective view of an alternative embodiment of the present design;

FIG. 9 is a front view of the embodiment of FIG. 8 of the present design;

FIG. 10 is a rear view of the embodiment of FIG. 8 of the present design;

FIG. 11 is a right side view of the embodiment of FIG. 8 of the present design;

FIG. 12 is a left side view of the embodiment of FIG. 8 of the present design;

FIG. 13 is a top view of the embodiment of FIG. 8 of the present design;

FIG. 14 is a bottom view of the embodiment of FIG. 8 of the present design;

FIG. 15 is a perspective view of an alternative embodiment of the present design;

FIG. 16 is a front view of the embodiment of FIG. 15 of the present design;

(Continued)

FIG. 17 is a rear view of the embodiment of FIG. 15 of the present design;
FIG. 18 is a right side view of the embodiment of FIG. 15 of the present design;
FIG. 19 is a left side view of the embodiment of FIG. 15 of the present design;
FIG. 20 is a top view of the embodiment of FIG. 15 of the present design;
FIG. 21 is a bottom view of the embodiment of FIG. 15 of the present design;
FIG. 22 is a perspective view of an alternative embodiment of the present design;
FIG. 23 is a front view of the embodiment of FIG. 22 of the present design;
FIG. 24 is a rear view of the embodiment of FIG. 22 of the present design;
FIG. 25 is a right side view of the embodiment of FIG. 22 of the present design;
FIG. 26 is a left side view of the embodiment of FIG. 22 of the present design;
FIG. 27 is a top view of the embodiment of FIG. 22 of the present design;
FIG. 28 is a bottom view of the embodiment of FIG. 22 of the present design;
FIG. 29 is a perspective view of an alternative embodiment of the present design;
FIG. 30 is a front view of the embodiment of FIG. 29 of the present design;
FIG. 31 is a rear view of the embodiment of FIG. 29 of the present design;
FIG. 32 is a right side view of the embodiment of FIG. 29 of the present design;
FIG. 33 is a left side view of the embodiment of FIG. 29 of the present design;
FIG. 34 is a top view of the embodiment of FIG. 29 of the present design;
FIG. 35 is a bottom view of the embodiment of FIG. 29 of the present design;

FIG. 36 is a perspective view of an alternative embodiment of the present design;
FIG. 37 is a front view of the embodiment of FIG. 36 of the present design;
FIG. 38 is a rear view of the embodiment of FIG. 36 of the present design;
FIG. 39 is a right side view of the embodiment of FIG. 36 of the present design;
FIG. 40 is a left side view of the embodiment of FIG. 36 of the present design;
FIG. 41 is a top view of the embodiment of FIG. 36 of the present design; and,
FIG. 42 is a bottom view of the embodiment of FIG. 36 of the present design.
